UNITED STATES PATENT OFFICE.

GUSTAVE CLÉMENT D'ARDOYS AND GEORGES DÉSIRÉ LOIZON, OF OZOIR LA FERRIÈRE,
FRANCE.

PEDAL FOR CYCLES AND LIKE VEHICLES.

1,230,129.

Specification of Letters Patent. Patented June 19, 1917.

Application filed March 27, 1913. Serial No. 757,135.

To all whom it may concern:

Be it known that we, GUSTAVE CLÉMENT D'ARDOYS and GEORGES DÉSIRÉ LOIZON, both citizens of the Republic of France, and residing at Ozoir la Ferrière, in the Republic of France, have invented certain new and useful Improvements in and Relating to Pedals for Cycles and like Vehicles, of which the following is a specification.

10 This invention has reference to an adjustable vertical balancing device for the pedals of cycles and like vehicles, with or without toe-clips, the purpose of which is to maintain as far as possible, the pedals 15 in their horizontal position.

We will now describe our invention with reference to the accompanying drawing showing several forms of construction of a balancing device, in which:—

20 Figure 1 shows the preferred form of a balancing device for pedals provided with heavy toe-clips with or without strap, the toe-clip being shown in the drawing just as it is stamped out.

25 Fig. 2 is a front elevation of the complete balancing device according to the present invention.

Fig. 3 is a side view of the same, and

30 Fig. 4 is a perspective view of a pedal with the device secured thereto.

The plate α of the balancing device is secured to the rear bar of the pedal P by means of bolts or the like passing through slots b' of the plate and the bar.

35 As shown, the plate α is bent at right angles along the line B—B and forms an angle, one branch of which is formed with a slot h in which engages a threaded bolt i with a head j and three nuts k . One of 40 these nuts is adapted to fasten the weight

box d having a cover d' as shown in Fig. 2 against the head j and the two other nuts k permit adjustment of the bolt i as to height. The box d is adapted to receive a number of calibrated lead disks which are 45 separated from the bottom and the top of the box and from each other by anti-rattling washers. This construction permits consequently, a triple regulation, first, by the movable weight box with variable load, 50 second by the threaded bolt adjustable to a desired height and third by displacement of said bolt i in the slot h forward or backward.

What we claim is:

1. Balancing device for the pedals of cycles or the like comprising an angularly bent perforated plate adapted to be secured to the back part of a pedal, a box secured to said plate and exchangeable means with- 60 in said box for regulating the balancing power of the device to suit the weight to be balanced.

2. Balancing device for the pedals of cycles or the like comprising an angularly bent perforated metal plate adapted to be secured to the back bar of a pedal, a box secured to said plate and calibrated metal plates or disks within said box separated by felt layers and exchangeable for regu- 65 lating the balancing power of the device to correspond to the weight to be balanced.

In testimony whereof we affix our signatures.

GUSTAVE CLÉMENT D'ARDOYS.
GEORGES DÉSIRÉ LOIZON.

In the presence of—

VICTOR PREVOST,
BARTLEY F. YOST.
